VACUUM TUBE

Paul Georges Chevigny, New York, N. Y., and Carson McKeag Wheeler, Montclair, N. J., assignors to Federal Telephone and Radio Corporation, Newark, N. J., a corporation of Delaware

Application March 26, 1943, Serial No. 480,662

12 Claims. (Cl. 250—27.5)

1

This invention relates to improvements in vacuum tubes, and more particularly to novel arrangements for the mounting of cathodes in magnetrons.

An object of this invention is to provide a novel magnetron construction having large heat-dissipating surfaces.

Another object of this invention is directed to novel arrangements for mounting the cathode in such magnetrons.

A further object of this invention is to provide improved lead-in arrangements for supporting the cathode in a magnetron.

Other objects will become apparent from the following description taken in connection with the attached drawings showing several illustrative embodiments of the invention, and wherein:

Fig. 1 is a longitudinal broken cross-sectional view of a preferred form of magnetron structure formed in accordance with the present invention;

Fig. 2 is a transverse cross-sectional view taken along line II—II of Fig. 1;

Fig. 3 is a partial broken longitudinal sectional view of a modified form of magnetron cathode mounting;

Fig. 4 is a transverse cross-sectional view taken along the line IV—IV of Fig. 3;

Fig. 5 is a broken partial longitudinal cross-sectional view of still another form of lead-in construction; and

Fig. 6 is a transverse cross-sectional view taken along the line VI—VI of Fig. 5.

In the preferred form of invention illustrated in Figs. 1 and 2, the magnetron is formed of a hollow metal pipe 10 whose central bore 11 is preferably, but not necessarily, formed square. A cathode 12 is placed within the bore 11 and within a transverse opening 13 extending through one wall of the pipe. Opposed magnets 14, 14' are adapted to be positioned about the pipe 11 opposite the cathode 12. One end of the pipe 10 is formed with a seal which may consist of a cap 16 screwed about the end of the pipe 10. For the purpose of coupling the magnetron output to other devices, the cap 16 may be formed with a central opening and presses a copper disk 18, having a narrow slot 20, against the end of the pipe. A mica disk 22 is placed over the open end of the copper disk 18 and may be sealed to the cap 16 by suitable means, such as a varnish seal. It is to be understood however, that the coupling seal just described may be replaced by other types of seals or coupling devices, such for example, as described in the copending applica-

tion of P. G. Chevigny, S. N. 481,314, filed March 26, 1943 now Patent No. 2,419,536.

The other end of the pipe 10 is also sealed as by a cap 24. This cap covers the central bore 11 but is provided with a pair of spaced openings into which are fitted outwardly extending sleeves 26, 26' aligned with small longitudinal bores 28, 28' communicating with the cavity formed by the intersection of the transverse passage 13 with the central bore 11. The outer ends of the sleeves 26, 26' are sealed as by glass seals 30, 30' respectively, through which extend lead rods 32, 32'. These rods project outwardly from the seals 30, 30' and inwardly through the sleeves 26, 26' and bores 28, 28' for connection with the cathode 12. This cathode which is preferably formed of a hollow cylinder provided on its outside with some suitable electron-emitting coating is formed at one end with an extension 34 held in a bushing 36 attached to the end of the one lead 32. Within the cathode 12 is a suitable heating element such as a spiral filament 38 which is connected at one end to the extension 34 and at its other end to the other lead rod 32'. The passage 13 is closed on the outside by a cap 40 which is sealed in place in any suitable manner after the parts have been assembled within the passage.

It will thus be seen from a study of Figs. 1 and 2 that we have provided a magnetron structure in which all parts are readily accessible and which, while the various electrodes are mounted within a sealed evacuated chamber, provides a larger heat-dissipating surface for the pipe 10 which forms the anode and the outer portion of the resonant chamber of the tube. As a result, the tube may not only be operated at extremely high frequencies but since the pipe 12 is accessible for readily cooling by any suitable well-known means, (not shown) it is capable of handling large amounts of power.

In Figs. 3 and 4 we have illustrated a modified arrangement in which the leads for the cathode extend transversely through the side walls of the pipe rather than longitudinally thereof, as in Figs. 1 and 2. As is shown in Figs. 3 and 4, the tube again is formed of a long hollow pipe 110 whose central bore 111 is preferably of square cross-section. The cathode 112 is mounted in a similar transverse passage 113 while opposed magnets 114, 114' are positioned about the pipe on opposite sides of the cathode. In this case, however, the bores 128, 128' extend transversely through one wall of the pipe 110 and communicate with the cavity formed by the intersection of the transverse passage 113 with the longitudinal

bore 111. Sleeves 126, 126' are fastened partially within the bores 128 and 128' respectively, and their outer ends are covered by glass seals 130, 130'. Lead 132 extends through the glass seal 130 at one end and connects with the extension 134 on one end of the cathode 112 by means of the bushing 136. The other lead 132' extends outwardly through the seal 130' and inwardly through the sleeve 126' and bore 128' to within the central cavity where it is connected to the lower end of the heating coil 138. A cover 140 closes the passage 113. One end of the pipe 110 may be sealed with a coupling seal as in the manner described in connection with Figs. 1 and 2, while in this case the other end will be formed by a straight seal which may be in the form of a cap 124.

In the form of invention illustrated in Figs. 5 and 6, the cathode leads extend transversely into the pipe in alignment and from opposite sides. Again, the magnetron consists essentially of a hollow longitudinal pipe 210 having a preferably square central bore 211. A cathode 212 is positioned within the bore 211 at the intersection of the latter with a transverse passage 213. Magnets 214, 214' are positioned outside of the pipe 210 on opposite sides of the cathode 212.

The bores 228 and 228' extend outwardly through the walls of the pipe 210 at right angles to the central bore 211 but in alignment with one another. The bore 228 contains an outwardly extending sleeve 226 whose periphery is closed by a glass seal 230. A lead 232 passes through the seal 230 inwardly to the cathode. The bore 228 contains the outwardly projecting sleeve 226' whose periphery is covered by the glass seal 230'. The lead 232' extends through this glass seal and inwardly toward the cathode 212. The cathode 212 in this case is formed with a tab 251 extending upwardly from the extension 234 and attached to one end of the lead 232 and a surrounding collar 252. The lower end of the heating coil 238 is connected to the lower end of the cylindrical cathode 212 while the upper end of the coil 238 extends through an opening at the top of the cathode and is attached to the inner end of the lead rod 232'.

It will be clear to those skilled in this art that the modifications illustrated in Figs. 3 to 6 inclusive are fundamentally similar to the preferred form of construction illustrated in Figs. 1 and 2, but provide for different arrangements of the tube which, under various circumstances may be more suitable than the construction shown in the preferred form. The essential feature, namely, providing a large accessible anode surface which can be readily cooled for the purposes of increasing the handling capacity of the tube is present in all forms of the invention.

While we have illustrated in connection with the present invention only one type of cathode structure, it will be clearly understood by those skilled in this art that the arrangement of cathode leads in accordance with the present invention permits the use of various other types of cathodes, for example, one might use a cathode indirectly heated by bombardment, as is shown in the copending application of P. G. Chevigny, S. N. 474,968, filed February 6, 1943, now Patent No. 2,411,506, or a directly heated cathode may be used as well as an indirectly heated cathode. Therefore, while we have described above the principles of our invention in connection with certain specific apparatus and particular modifications thereof, it is to be clearly understood that

this description is made only by way of example and not as a limitation on the scope of our invention as set forth in the objects and the accompanying claims.

5 We claim:

1. An electron discharge device, including a hollow metal pipe formed with a transverse passage in one wall leading to its central bore and forming therewith a central cavity, and a pair of 10 relatively smaller bores extending through its walls at an angle to said passage and communicating with said cavity, a cathode positioned within said cavity, cover means sealing the open end of said passage, a pair of cathode leads each attached at one end to said cathode and extending through said smaller bores outwardly of said pipe, means sealing the outer ends of said smaller bores and supporting said leads therein, a pair of magnets, one positioned on each side of said pipe in alignment with said cavity, and means sealing both ends of said pipe.

2. The combination according to claim 1, in which said cathode comprises a hollow cylinder and a heating coil positioned therein, said cylinder being disposed coaxially with respect to said cavity with one end of said coil connected to said cylinder, and in which one of said leads is connected to one end of said cylinder and supports the same, and the other lead is connected to the other end of said heating coil.

3. An electron discharge device, including a hollow metal pipe formed with a transverse passage through one wall leading to its central bore and forming therewith a central cavity, and a pair of relatively smaller bores extending through its walls at an angle to said passage and communicating with said cavity through one side thereof, a cathode positioned within said cavity, cover means sealing the open end of said passage, 35 a pair of cathode leads each attached at one end to said cathode and extending through said smaller bores outwardly through said pipe, means sealing the outer ends of said smaller bores and supporting said leads therein, a pair of magnets, one positioned on each side of said pipe in alignment with said cavity, and means sealing both ends of said pipe.

4. The combination according to claim 3, in which said cathode comprises a hollow cylinder and a heating coil positioned therein, said cylinder being disposed coaxially with respect to said cavity with one end of said coil connected to one end of said cylinder, and in which one lead is connected to the said one end of the cylinder, and the other lead to the other end of the heating coil.

5. An electron discharge device, including a hollow metal pipe formed with a transverse passage through one wall leading to its central bore and forming therewith a central cavity, and a pair of relatively smaller bores extending longitudinally through its walls from one end of the pipe to the central cavity, cover means sealing the open end of said passage, a cathode positioned within said cavity, a pair of cathode leads each attached at one end to said cathode and respectively extending through said smaller bores outwardly of the one end of the pipe, means sealing the one end of the pipe and supporting said leads, means sealing the other end of said pipe, and a pair of magnets, one positioned on each side of said pipe and in alignment with said cavity.

6. The combination according to claim 5, in which the sealing means for the one pipe end includes a cap on the end of the pipe closing the

central bore and having a pair of openings therethrough aligned with said smaller bores, a metal sleeve in each opening projecting outwardly therefrom, and a glass seal about the outer periphery of each sleeve and surrounding the enclosed leads.

7. An electron discharge device, including a hollow metal pipe formed with a transverse passage through one wall leading to its central bore and forming therewith a central cavity, and a pair of relatively smaller bores extending through its wall at an angle through said passage transversely to the axis of the central bore and communicating with said cavity, a cathode positioned within said cavity, cover means sealing the open end of said passage, a pair of cathode leads each attached at one end to said cathode and extending through said smaller bores outwardly of said pipe, means sealing the outer ends of said smaller bores and supporting said leads therein, a pair of magnets, one positioned on each side of said pipe in alignment with said cavity and means sealing both ends of said pipe.

8. The combination according to claim 7, in which the sealing means for said smaller bores comprises a metal sleeve in each bore extending outwardly through the walls of said pipe and a glass seal about the outer periphery of each sleeve sealing the same and surrounding the outwardly extending lead.

9. The combination according to claim 7, in which said smaller bores communicate with said central cavity through one end of said pipe.

10. An electron discharge device, including a hollow metal pipe formed with a transverse passage through one wall leading to its central bore and forming therewith a central cavity, and a pair of parallel transverse smaller bores extending through another wall and communicating with said cavity, cover means sealing the outer end of said passage, a cathode positioned within said cavity, said cathode comprising a hollow cylinder and a heating coil positioned therewith having one end attached to one end of the cylinder, a pair of cathode leads extending through said smaller bores outwardly of said pipe, one cathode lead being connected to the one end of the cylinder and the other cathode lead being

connected to the other end of said heating coil, a metal sleeve in each of the smaller bores surrounding said leads and extending outwardly of said pipe, a glass seal about the periphery of the outer end of each sleeve, enclosing and supporting the outwardly extending leads, a pair of magnets, one positioned on each side of said pipe in alignment with said cavity, and means sealing both ends of said pipe.

- 10 11. An electron discharge device, including a hollow metal pipe formed with a transverse passage through one wall leading to its central bore and forming therewith a central cavity, and a pair of smaller aligned transverse bores extending through opposite walls and communicating with said cavity, a cathode positioned within said cavity, cover means sealing the open end of said passage, a pair of cathode leads each attached at one end of said cathode and extending through said smaller bores outwardly of said pipe, means sealing the outer ends of said smaller bores and supporting said leads therein, a pair of magnets one positioned on each side of said pipe in alignment with said cavity and means sealing both ends of said pipe.
- 15 12. The combination according to claim 11, in which said cathode comprises a hollow cylinder and a heating coil positioned therein, said cylinder being disposed coaxially with respect to said cavity with one end of said coil attached to one end of the cylinder, and in which one of said leads is connected to the other end of said cylinder and the other of said leads is connected to the other end of said heating coil.

35 PAUL GEORGES CHEVIGNY.
